J. N. BRANDELLE,
BATH CABINET,
APPLICATION FILED NOV. 15, 1913.

1,157,842.

Patented Oct. 26, 1915.

UNITED STATES PATENT OFFICE.

JOSEPH N. BRANDELLE, OF CHICAGO, ILLINOIS.

BATH-CABINET.

1,157,842.

Specification of Letters Patent.

Patented Oct. 26, 1915.

Application filed November 15, 1913. Serial No. 801,126.

To all whom it may concern:

Be it known that I, JOSEPH N. BRANDELLE, a citizen of the United States, residing at Chicago, Cook county, Illinois, have invented 5 certain new and useful Improvements in Bath-Cabinets, of which the following is a specification.

My invention relates to bathing cabinets and has particular reference to portable 10 cabinets for hot or steam baths.

The object of the present invention is to not only utilize an ordinary bath tub as a part of the cabinet, but to make the bath tub attachment convenient to mount on a tub, 15 convenient to adjust to a person, comparatively inexpensive and simple in its form of construction, and constructed and arranged to fold up into a thin, compact form so that it may be stored in a small space and adapted 20 for use in small compartments to which other forms of these structures would be inapplicable because of lack of space.

With these objects in view the invention consists in the novel construction, combination 25 and arrangement of parts, hereinafter described in detail, illustrated in the accompanying drawing and incorporated in the appended claims.

In the drawing—Figure 1 is an elevation, 30 partly in section, of a cabinet embodying my invention together with the figure of a user. Fig. 2 is a section on line 2—2 of Fig. 1, the human figure being omitted. Fig. 3 is a perspective view of the hood or attachment, 35 dotted positions showing the beginning of the folding up movement. Fig. 4 shows the top or hood folded up.

In the several views 2, represents an ordinary bath tub equipped with a faucet 3 for admitting water thereinto and the usual accessories which are not modified by the present invention. This tub is made a part 40 of my steam-bath cabinet by the addition of a top or hood composed of a frame to lie on the top or edges of the tub, consisting of arched members 4 and 5, and three-sided frame-members 6 and 7, all these members being hinged together at their ends at 8 and 9. Between the members 4 and 6 and 5 and 45 7, respectively, extend flexible coverings made of rubber, canvas or other suitable material 10 and 11. A circular opening 12 for the neck of a person 13 is formed in the upper horizontal portions of the frames 6 and 7 by each of these frames being formed with a semi-circular middle portion, the por-

tion for the frame 6 being designated as 14 and that for the frame 7 as 15. The usual method for providing steam or heated air is to place a burner or heater 16 within the 60 cabinet and connect it through a tube or wires 17 with any nearby fixture. A vessel adapted to be mounted on the burner and contain steaming water is indicated in Fig. 1 as 18. 19 represents an indentation in the 65 frame which provides for space between the frame and the tub for the tube or wires 17. The hood is fastened temporarily to the tub by means of spring clips 20 and 21 which engage the rim of the tub at any suitable 70 number of points.

In Fig. 3 the dotted lines show how the frame members 6 and 7 are parted to be lowered onto the members 4 and 5, or as much as necessary, to admit the entrance of 75 the person, and other dotted lines show how the frame members 4 and 5 are raised to fold them up against the members 6 and 7 for storage purposes after each service.

By utilizing the whole bath tub as a part 80 of the cabinet it may be partially heated by flushing the tub with hot water from its faucet, wetting the bath room floor is obviated, a steam bath may be taken in a common size of bath room too small to contain 85 a separate cabinet besides the usual bath room fixtures, a plunge bath may be taken after the steam bath without leaving the tub, a foot bath may be taken at the same time 90 the steam bath is taken, and scarcely any 95 appreciable time is required to prepare for the bath and to put away the attachment or hood after a steam bath has been taken. By making the rim or frame resting on the tub rim, composed of members 4 and 5, several inches wide the same hood may be made to fit several sizes of tubs without resorting to means for shortening or changing the width and length of said frame.

Having thus described my invention I 100 claim as new and desire to secure by Letters Patent—

1. The combination with a bath tub of a frame in two hinged together sections adapted to overlie the edges of said tub, frame members each having a neck opening therein and hinged together, and a covering in two separate sections for said frame and frame members forming a hood or added chamber on and over said bath tub. 105

2. The combination with a bath tub, of the horizontal frame members 4 and 5 adapt-

ed to rest upon the edges of a bath tub, the vertical frame members 6 and 7 pivoted to said members 4 and 5, and the coverings 10 and 11 which together form the opening 12 when brought together, said members 4, 5, 6, 7 and coverings 10 and 11 folding together as specified.

In testimony whereof I have hereunto set my hand in the presence of two subscribing witnesses.

JOSEPH N. BRANDELLE.

Witnesses:

C. F. PETERSON,
P. V. BRANDELLE.
